VENDING MACHINE FOR CARTONS OF MILK, BOTTLED BEVERAGES OR THE LIKE

Floyd V. Bookout, Independence, Mo., assignor to The Vendo Company, Kansas City, Mo., a corporation of Missouri

Application July 9, 1956, Serial No. 42,176

Term of patent 14 years

(Cl. D52—3)

The single figure is a front perspective view of a vending machine for cartons of milk, bottled beverages or the like, showing my new design.

The opposite side of said machine is substantially the same in appearance as the side shown, and the rear is unadorned.

I claim:

The ornamental design for a vending machine for cartons of milk, bottled beverages or the like, as shown and described.
